UNITED STATES PATENT OFFICE.

GEORGE W. HOYT, OF CHICAGO, ILLINOIS.

DESIGN FOR A STOCKING-SUPPORTER CLASP.

SPECIFICATION forming part of Design No. 21,114, dated October 13, 1891.

Application filed September 17, 1891. Serial No. 406,031. Term of patent 14 years.

To all whom it may concern:

Be it known that I, GEORGE W. HOYT, a citizen of the United States, residing at Chicago, in the county of Cook and State of Illinois, have invented and produced a new and original Design for Stocking - Supporter Clasps, of which the following is a specification.

The object of my design is to provide a novel and ornamental stocking - supporter clasp; and the leading features thereof reside in a raised bead extending round the inner and outer edges of the side bars of the clasp, with the portion intermediate the inner and outer ribs reduced in thickness to make the beads prominent.

In the accompanying drawings, Figure 1 is a plan view of the stocking-supporter clasp; and Fig. 2 is a transverse sectional view of the same, taken on the line $x-x$, Fig. 1.

In the drawings, the numerals 1 and 2 indicate the cross-bars at the top of the stocking-supporter clasp, and 3 and 4 indicate the raised beads, which extend round the inner

and outer edges of the side bars of the clasp. The side bars of the clasp extend downwardly from the cross-bars for a part of their length and then converge and join each other at the lower extremity of the clasp. The side bars are reduced in thickness between the inner and outer ribs 3 and 4, and the surface of such reduced intermediate portion is rendered ornamental by being milled or serrated, as at 5. The reduced portion of the side bars between the inner and outer ribs, as described and shown, provides a novel and ornamental stocking-supporter clasp.

What I claim is—

The design for a stocking-supporter clasp, substantially as shown and described.

In testimony whereof I have hereunto set my hand and affixed my seal in presence of two subscribing witnesses.

GEORGE W. HOYT. [L. S.]
